UNITED STATES PATENT OFFICE.

EUGENE R. CARICHOFF, OF SCHENECTADY, NEW YORK, ASSIGNOR TO GENERAL ELECTRIC COMPANY, A CORPORATION OF NEW YORK.

FUSE CUT-OUT.

1,055,877.

Specification of Letters Patent.

Patented Mar. 11, 1913.

Application filed October 12, 1911. Serial No. 654,229.

To all whom it may concern:

Be it known that I, EUGENE R. CARICHOFF, a citizen of the United States, residing at Schenectady, county of Schenectady, State 5 of New York, have invented certain new and useful Improvements in Fuse Cut-Outs, of which the following is a specification.

My invention relates to fuse cut-outs for protecting circuits of comparatively high 10 voltage and large currents, and its object is to provide a fuse which will rupture such a circuit upon an overload more positively and instantaneously than the fuses employed heretofore.

15 I obtain the desired result by forming the fuse member so that its current carrying capacity is reduced at a plurality of points along its length and providing means for ejecting the portion of said member between 20 said points upon rupture at said points. With this construction the fuse is ruptured upon overload at two points and the portion between those points bodily expelled so as to leave a wide gap. This produces less gas 25 than the ordinary fuse, in which rupture occurs at a single point so that it is necessary to burn away a considerable length of the fuse before the arc breaks. Furthermore, I have found by oscillograph tests 30 that a fuse constructed in accordance with my invention breaks a circuit immediately and finally under conditions in which a fuse of the ordinary construction allows the circuit to reestablish itself one or more times 35 through the conductive gases of combustion. Furthermore, if a magnetic blow-out is employed for expelling the ruptured portion, it may be arranged very efficiently with a fuse of my improved construction as will be 40 hereinafter pointed out.

My invention will best be understood by reference to the accompanying drawings in which—

45 Figure 1 shows a side elevation, with the casing in cross-section, of a fuse cut-out arranged in accordance with my invention and Fig. 2 shows an enlarged plan view of the fuse member.

50 In the particular embodiment of my invention shown in the drawings A represents the fuse member which has its current carrying capacity reduced at two points by holes a, a, which reduce the cross-section at this point as is shown in Fig. 2. The ends of

this fuse member are clamped in suitable 55 terminal blocks B, B by means of wedges b, b which are drawn up by knurled screws C, C.

D, D represent blow-out coils at opposite ends of the fuse and in series therewith. 60 From these coils magnetic pole pieces E (shown in dotted lines in Fig. 1) extend adjacent to the points a, a of reduced capacity of the fuse member. It will be understood that there is a pair of pole pieces E opposite 65 each other for each coil D, so that the flux passes between the pole pieces of each pair in a direction perpendicular to the plane of the paper in Fig. 1.

F, F represent the usual insulating barriers forming the arc chute.

The operation of the fuse cut-out will be obvious from the foregoing description. Upon an overload or short circuit the fuse member A is ruptured at the points a, a, 75 and the portion between these points is ejected by the magnetic fields formed at these points between the pairs of pole pieces E. Thus a wide gap is formed in the circuit, and the circuit is consequently immediately 80 and positively ruptured with a comparatively small production of gas.

It will be noted that the tips of the pole pieces E may be brought directly opposite the points a, a on the fuse member so that 85 strong fields are produced precisely at the points where they are needed, while in the fuse of ordinary construction, with a single hole at its center, the pole pieces E extending from opposite ends of the fuse member 90 must be kept separate and cannot be brought together without impairing the insulation, so that they cannot extend to the exact center of the fuse member at which rupture takes place in the ordinary construction.

I do not desire to limit myself to the particular arrangement and construction of parts shown and described but aim in the accompanying claims to cover all modifications which are within the scope of my invention.

What I claim as new and desire to secure by Letters Patent of the United States, is,—

1. In a fuse cut-out, a fuse member having a plurality of portions in series of reduced current carrying capacity, coils at each end of said fuse member in series

therewith, and magnetic pole pieces extending from said coils to points adjacent to said portions of reduced capacity.

2. In a fuse cut-out, a fuse member having a plurality of portions in series of reduced current carrying capacity, coils at each end of said fuse member in series therewith, magnetic pole pieces extending from said coils to points adjacent to said portions of reduced capacity, and insulating barriers

extending from each end of said fuse member past said coils and forming an arc directing chute between said pole pieces.

In witness whereof, I have hereunto set my hand this 11th day of October, 1911.

EUGENE R. CARICHOFF.
